METHOD OF AND APPARATUS FOR DETERMINING BORE ALIGNMENT OF TUBES

John S. Morgan, Jr., Hermosa Beach, Calif., assignor to The National Supply Company, Pittsburgh, Pa., a corporation of Pennsylvania

Application June 25, 1938, Serial No. 215,899

12 Claims. (Cl. 33—46)

This invention relates to a method and apparatus for determining the bore alignment of tubular members, and is particularly directed to a method and apparatus for determining the deviations between the geometrical axis of a tube and an axis of the hole of the tube. While the method and apparatus of this invention is applicable for use in connection with any tubular member, it is particularly designed and applicable for use in connection with such tubes as are employed in well drilling art and will be particularly described in connection therewith.

In the rotary system of drilling wells, a hollow rod or tube is employed having attached to its lower end a drill or cutting member. A lubricating medium or fluid is conducted through the tube to the bit. As wells are drilled to considerable depths, the tube is formed in sections which are connected in end to end relation. The uppermost section of this drilling tube is generally formed with a non-circular cross-section in order that rotation may be imparted thereto by surface machinery. The uppermost section is generally known as the "grief stem" or kelly. The lowermost section of this tubular drill string is known in the art as the drill collar. The drill collar and grief stem or kelly are customarily made by drilling or boring longitudinally through a solid bar. Every effort is made to make the bore hole straight and true with the geometrical axis of the bar, as any appreciable variation is likely to cause the completed kelly or drill collar to rotate eccentrically or "whip" at high speeds. Also any variation in the bore of such kellys or drill collars is liable to result in a weakened section which, under the magnitude of the loads carried, is liable to result in failure of the drill stem under operation. Due however to inherent limitations in boring equipment, variations in bore alignment may be present which may be of greater magnitude than permissible.

It is accordingly an object of my invention to provide a method for determining the magnitude of variations between the geometrical axis of the kelly or drill collar and the axis of the bored hole extending therethrough.

Another object of this invention is to provide a device for determining bore alignment of tubes, which device is operable to determine the variation of the bored hole with reference to the geometrical axis of the tube, and which means includes a member adapted to be inserted within the bored hole of the tube and to be moved therethrough and which, during its movement in or with relation to the tube, will assume a position

within the tube with relation to the geometrical axis of the tube, thereby enabling the relative relation of the said axis to be determined by observation of the position of said device within the said tube.

Another object of this invention is to provide a means adapted to be positioned within a bore of a tube which is so constructed as to gravitate freely within the bore hole to the lowest position therein so that observations or determinations of its position may be made to determine the relation of such bore to the geometrical axis of the tube.

Other objects and advantages of this invention it is believed will be apparent from the following detailed description of a preferred embodiment thereof as illustrated in the accompanying drawings.

In the drawings:

Figure 1 is an elevation mainly in vertical section of an apparatus embodying my invention.

Figure 2 is an end elevation of the apparatus as illustrated in Figure 1 looking from the left toward the right.

Figure 3 is an end elevation taken substantially on the line 3—3 of Figure 1.

Figure 4 is an end view partly in section of the feeding means embodied in my invention.

Figure 5 is a diagrammatic view illustrating the initial position of the sighting apparatus crosshairs with reference to a target at the start of the operation.

Figure 6 is a similar diagrammatic view illustrating the relative position of the crosshairs after a tubular member has been revolved through a half turn and wherein the axis of the bore hole is offset with relation to the geometrical axis of the tube.

Figure 7 is a sectional end view showing a non-circular member or kelly rotatably supported by adapters.

Figure 8 is a side view of the adapter illustrated in Figure 7.

Figure 9 is a diagrammatic view of a modified form of apparatus embodying my invention.

Figure 10 is a diagrammatic view of a further modification of my invention.

In the determination of the bore alignment of tubes, I have found that it is not sufficient merely to measure the displacement of the axis of the bore with reference to the geometrical center of the tubular member because as the bore hole deviates from the axis of the tubular member, it may, and generally does, vary in different relationships to the straightness of the tubular mem-

ber and to the wall thickness. The axis of the bore may coincide with the geometrical axis of the tubular member in one plane with the tube setting in one position and may deviate widely in another plane from that axis. As the ultimate determination desired is of the relative wall thickness at the different points, I have found that it is essential in carrying out my method of determining the bore of such a tubular member 5 to mount in the bore a member which will gravitate to the low point of the tubular member as the tubular member is rotated so that the failure of the axis of the bore to coincide with the geometrical axis of the tubular member may be taken 10 with relation to that point of the wall of the tubular member which is the most thin at the point of the determination. In accordance with my invention I therefore provide a target or determining member which is mounted within the bore of the tubular member in such position as to gravitate to the lowest point of the tubular member as the tubular member is rotated. Thus a determination is made at that point where the tube is the thinnest. A second determination may 15 then be made by rotating the tube through substantially 180° and by the two determinations or readings the degree of deviation of the bore axis to the geometrical axis of the tube may be determined.

30 In the modification of my invention as illustrated in Figures 1 to 8, inclusive, there is illustrated a plurality of supports 1 which rotatably support the tubular member 2 upon which the determination is to be made. A sighting apparatus is indicated at 3, positioned with relation to the tubular member 2 so as to view the position of a target carrier 4 within the bore 5 of the tubular member 2. The target carrier 4 is adapted to be progressed through the bore 5 by means 35 of a feed mechanism 6. Means are also provided for example such as the motor indicated at 7 for rotating the tubular member 2 upon the supports 1.

40 Rollers 8 are carried at the upper ends of the supports 1 to allow the tubular member 2 to rotate about its geometrical axis.

45 It will be obvious that any convenient or desirable number of such supports 1 may be used, depending upon the length of the member 2 upon which the determination is to be made. As herein illustrated, the member 2 is a drill collar. In order to rotate the drill collar 2, a split sprocket 9 is clamped around the tubular member 2 and a chain 10 is passed over this sprocket and over 50 a corresponding sprocket mounted upon the power take-off shaft of the motor 7. Any suitable or desirable form of gear reduction mechanism may be interposed between the motor 7 and the chain 10 as indicated at 11 for reducing the speed of 55 drive to that desired.

60 The target carrier 4 is mounted upon rollers 12 to permit the target to rotate as the drill collar is rotated. The rollers 12 are, as illustrated, secured to the body of the carriage 4 in such a manner as to be nonrotative relative to the carriage 4, thus causing the entire carriage 4 to rotate as the drill collar 2 is rotated, with the result that the target carrier 4 as it rolls gravitates to the lowest portion of the bore hole 5.

65 Secured to the carriage 4 is a plug 13 to which the cable 14 is secured by means of a swivel connection 15. The cable 14 extends to the feed mechanism 6 so that through the medium of the cable 14 and feed mechanism 6, the target carriage 4 may be pulled through the tubular mem-

ber 2. A second target plug 16 is secured within the concentrically formed bore of the carriage 4 and this target plug 16 is formed upon its outer face with a scale 17 consisting of a plurality of concentrically disposed and preferably equally spaced lines 18. The center of this scale corresponds with the centers of the rollers 12 which support the carriage 4. The scale 17 may be illuminated by any suitable or desirable means and is herein illustrated as being illuminated by means of an electric globe 19 mounted within the carriage immediately in advance of the scale 17. Electric current is supplied to the globe 19 through insulated cable 20 mounted in the carriage 4 which is electrically connected as indicated at 21 with the cable 14. The entire pipe or tubular member 2 is grounded to form the opposite electrical connection.

20 The feeding device designated at 6 is indicated as including a support 22 upon which a cable drum 23 is rotatably mounted and adapted to be driven by a motor 24. The motor 24 may be provided with a worm pinion 25 which drives a worm wheel 26 carried upon the shaft to which the drum 23 is secured. The worm wheel 26 may 25 also be provided with a lug 27 which is adapted to trip a switch 28 to stop the motor 24 after the drum 23 has completed one revolution. The diameter of the drum 23 is such that one revolution thereof serves to draw the target carriage 4 30 through the bore hole 5 for the desired distance between readings.

35 A stationary brush 29 contacts a ring 30 carried by the drum 23 to supply electric current to the cable 14.

40 The sighting instrument 3, as illustrated, is adjustably mounted upon a support 31 and may consist of a telescope 32 provided with crosshairs 33 (Figs. 5 and 6). The crosshairs 33 are used in connection with the scale 17 to determine the 45 alignment of the bore hole 5 with the outer circumference of the drill collar 2.

45 Positioned adjacent the sighting instrument 3 is a control panel 34 which carries switches to control the supply of current to the motors and the light globe 19. As illustrated, the switch 35 controls the motor 7 for rotating the tubular member 2. The switch 36 operates to complete the electrical connection to the light globe 19 and the switch 37 operates to complete the electrical 50 connection to the motor 24 and for resetting the switch 28.

55 When the bore of a non-circular member is to be determined, which non-circular member may consist of the grief stem or kelly 2a, collars 38 are secured in spaced relation on the flat surfaces of the kelly and are adjusted in position by means of the adjusting screws 39 so that the geometrical axis of the kelly passes through the center of the circle of each collar 38. The collars are then rotatably supported by the rollers 8, thereby affording a rotatable mounting for the kelly about its geometrical axis. As herein illustrated, the collars 38 are provided with peripheral grooves 40 within which the rollers 8 are adapted 60 to operate.

65 The method of and operation of determining the bore alignment using this form of apparatus is: The kelly, drill collar or the like, is mounted upon the rollers 8 and the split sprocket 9 is clamped in position and connected to the motor 7. The target carriage 4 is placed in position within the bore hole and the globe 19 is lighted. The telescope 32 is adjusted as to height upon the adjustable support by means of the hand-wheel 70 75

41 and the observer sights through the telescope 32 and by means of the adjustment screws 42 and 43 brings the crosshairs 33 into approximate position with respect to the center of the target scale 17. The member 2 is then rotated through one or more complete revolutions while the observer watches for any vertical movement of the scale 17 with relation to the crosshairs 33. When the scale 17 reaches its lowermost position, the motor 7 is stopped and the telescope 32 is adjusted to place the crosshairs 33 in a position as illustrated in Figure 5. The telescope 32 is then in its reference position, and this setting remains unchanged until the target 5 moves to a new position or station within the bore hole 5.

An indicator ring 44 is attached to the member 2 by any convenient manner so that a pointer 45 is directed to a zero reading when the telescope is adjusted as indicated in Figure 5. This ring 44 rotates with the member 2 and its position thereon remains unchanged throughout the test. The motor 7 is then restarted and the member 2 slowly revolves while the observer 5 watches for the outermost scale to reach its highest position. When this position is reached, which position is indicated in Figure 6, the motor is stopped and the reading of the scale 17, as well as the angle reading of the indicator 44, are recorded. In the initial position of the target 4, the high position of the scale 17 will occur at 180° as illustrated in Figure 5, but for other positions of the target along the bore hole this may not be the case, particularly if the bore hole "spirals" 5 through the member 2.

It will be apparent that vertical movement of the scale 17 indicates that the bore hole 5 and the outer circumference of the drill collar are eccentric at the position of the target and that the amount of eccentricity is shown by the scale 17, and that the relative direction of eccentricity is shown by the reading of the indicator ring 44.

After this first reading has been taken, the observer presses one of the buttons of the switch 36, which causes the motor 24 to operate, thereby pulling the target to a new position within the bore hole 5. The observer then rotates the tube 2 by means of the motor 7 and the operation of taking the reading is repeated for each station at which the target carriage 4 is stopped, until the end of the bore 5 is reached. The record thus completed shows a chart of the amount and direction of deviation of the bore alignment for the entire tube.

In the modification of my invention as illustrated in Figure 9, the member 2^b upon which the determination is to be made may be mounted in position substantially as heretofore set forth in connection with the first modification of my invention. The target carriage 4^b in this case includes within its interior a lamp bulb 19^b which may be electrically connected in substantially the same manner as hereinabove set forth. Within the carriage 4^b is mounted a concentrating mirror 20^b which concentrates the light upon an aperture 50^b formed in a disc 51^b secured to the end of the carriage 4^b.

Supported by the carriage 4^b immediately in advance of the aperture is a concentrating lens 52^b. The light passing through the aperture 51^b is by this lens concentrated as a point of light directed to the end of the tube 2^b. Mounted at this point is a camera 53^b which may be of any suitable or desirable construction and in which there is mounted a motion picture film 54^b. In

this modification of my invention the carriage 4^b may be caused to continuously move through the tube 2^b and the cable 14^b is connected over a drum 23^b which is rotated through a worm and worm pinion drive by means of the motor 24^b. This same motor 24^b is connected through a series of gears 55^b to drive the drive mechanism of the motion picture camera 53^b and also through a continuation of this series of gears to drive a worm and rack 56^b which operates a moving stop 10 57^b which is connected through an arm 58^b with the lens 59^b of the camera 53^b so that a form of follow focus mechanism is provided to maintain the camera lens 59^b in substantial focus 15 with relation to the light beam emitted through the lens 52^b as the carriage 4^b is progressed through the tube.

With this form of mechanism a continuous record is formed of the vertical movement of the aperture 51^b upon the motion picture film 54^b, 20 thus giving a continuous and complete record of the amount of deviation of the bore hole 5^b of the member 2^b.

In the modification of my invention as illustrated in Figure 10, the method and means for 25 operating are substantially as illustrated in Figure 8 with the single exception of a frame 60 which is mounted at the end of the members 2 or 2^b and which frame provides a guideway for a carriage 61 in which a strip of sensitized film is 30 mounted. This sensitized film may be ruled as desired so that as the light emitted from, for example, the concentrating lens 52^b strikes the ruled and lined strip of sensitized film carried by the carriage 61, it forms thereon a record of the 35 movement of the said beam of light. In order to maintain this record in accordance with the travel of the carriage 4^b through the tubular member, the member 61 is driven transversely across the opening at the end of the tubular member 2 40 in timed relation with reference to the movement of the carriage 4^b through any suitable form of mechanism such, for example, as through the driving means as illustrated in connection with the second modification of my invention only in 45 that the worm gear mechanism 56^b is in this latter case operated to move the film carrier 61 transversely of the end of the tube 2^b in timed relation with the movement of the carriage 4^b.

Having thus fully described my invention and 50 several modifications thereof, it is to be understood that I do not wish to be limited to the details herein set forth, but my invention is of the full scope of the appended claims.

I claim:

1. In a device of the class described for determining bore alignment of a tube, the combination of means for mounting the tube for rotation about its longitudinal axis, means for rotating said tube about said axis, a target positioned within 60 the bore hole of the tube and having spaced supports adapted to contact the wall of said bore hole, a stationary sighting instrument independently and adjustably supported adjacent one end of the tube, said sighting instrument being 65 adapted for use in observing differences in position of said target upon rotation of the tube.

2. In a device of the class described for determining bore alignment of a tube, the combination of means for mounting the tube in a horizontal or 70 inclined position for rotation about its longitudinal axis, means for rotating said tube about said axis, a target positioned within the bore hole of the tube and having spaced supports adapted to contact the wall of said bore hole, a scale on said 75

target intermediate said spaced supports, a stationary sighting instrument adjustably supported adjacent one end of the tube, said sighting instrument being adapted for use in observing differences in position of said target scale upon rotation of the tube.

3. In a device of the class described for determining bore alignment of a tube, the combination of means for mounting the tube in a position other than vertical for rotation about its longitudinal axis, means for rotating said tube about said axis, a target positioned within the bore hole of the tube and having spaced supports adapted to contact the wall of said bore hole, a scale on said target, means associated with said tube including a calibrated ring and a pointer adapted to cooperate to indicate the angular position of the tube, a stationary sighting instrument independently and adjustably supported adjacent one end of the tube, said sighting instrument being adapted for use in observing differences in position of said target scale upon rotation of the tube.

4. In a device of the class described for determining bore alignment of a tube, the combination of supporting means for mounting the tube in a position other than vertical for rotation about its longitudinal axis, means for rotating said tube about said axis, a target having spaced rollers thereon of a diameter less than the diameter of the bore hole, said target being positioned within the bore hole and adapted to roll therein to gravitate to the lowest portion of its inner periphery, a stationary sighting instrument supported adjacent one end of said tube for observing said target, and means for moving said target longitudinally in said bore hole.

5. In a device for determining the alignment of a hole with respect to the longitudinal axis of the member through which it is bored, the combination of means for mounting the member in a horizontal position for rotation about said longitudinal axis, a target positioned within the bore hole and adapted to roll therein under the influence of gravity upon rotation of the member, and a telescope supported adjacent one end of said member for observing the maximum vertical movement of the target during one revolution of the member.

6. In a device for determining the alignment of a hole with respect to the longitudinal axis of the member through which it is bored, the combination of means for mounting the member in a horizontal position for rotation about said longitudinal axis, a target positioned within the bore hole and adapted to roll therein under the influence of gravity upon rotation of the member, a telescope adjustably supported adjacent one end of said member for observing the maximum vertical movement of the target during one revolution of the member, and means for moving said target by convenient increments longitudinally through the bore hole.

7. In a device of the class described for determining bore alignment of a tube, the combination of means for mounting the tube for rotation about its longitudinal axis, means for rotating said tube about said axis, a target positioned within the bore hole of the tube and having spaced supports adapted to contact the wall of said bore hole, said target being provided with a scale intermediate

said supports, means including a light source on said target adapted to illuminate said scale, a stationary sighting instrument adjustably supported adjacent one end of the tube, said sighting instrument being adapted for use in observing differences in position of said target scale upon rotation of the tube, means for moving said target by convenient increments longitudinally through the bore hole, the last said means including a cable adapted to carry electric energy to operate said light source.

8. In a device of the class described for determining bore alignment of a tube, the combination of means for mounting the tube for rotation about its longitudinal axis, a target positioned within the bore hole of the tube and provided with a scale, means to illuminate said target scale including a light source carried on the target, a stationary sighting instrument supported near one end of the tube and adapted for observing differences in position of said target scale upon rotation of the tube, means for moving said target longitudinally through the bore hole, the last said means including a cable adapted to carry electric energy to operate said light source.

9. A method of determining the alignment of the axis of a circular hole with respect to the longitudinal axis of the member through which it is bored, comprising supporting within the bore of the member an indicator so as to gravitate, rotating the member to cause the indicator to gravitate to the lowest point of the member, and simultaneously progressing the indicator longitudinally through the bore of the member, and producing a photographic record of the position of said indicator in a plane transverse of the hole as it travels the bore of the member.

10. In a device for determining the deviation of a bore from its theoretical axis, the combination of means for mounting said member through which the bore extends for rotation about said theoretical axis, a target positioned within the bore and adapted to roll by gravity circumferentially of the bore upon rotation of said member, and a telescope supported adjacent one end of said bore for optically measuring movement of the element radially of said theoretical axis as the member is rotated.

11. In a device for determining the deviation of a bore from its theoretical axis, the combination of means for mounting said member through which the bore extends for rotation about said theoretical axis, a target positioned within the bore and adapted to gravitate circumferentially of the bore upon rotation of said member, and means for optically measuring movement of the element radially of said theoretical axis as the member is rotated.

12. In a target for use within an elongated bore, the combination of a body provided with axially spaced roller elements for supporting the body within the bore, each of said elements being adapted to rotate in a plane normal to the axis of the bore, and a scale carried by the body and positioned intermediate said spaced roller elements.

JOHN S. MORGAN, JR.
